SHOULDERLESS GARMENT WITH
SUPPORTERPaul R. Swearingen, Kensington, Ohio, assignor
to George H. Bowman, Jr., Salem, Ohio

Application October 23, 1951, Serial No. 252,600

3 Claims. (Cl. 2—52)

1

The invention relates to an improved shoulderless garment of the type which is provided with a prehensile spring supporter, and the present application is a continuation in part of my co-pending application, Ser. No. 115,477, filed September 13, 1949, now abandoned.

Although the invention is especially adapted for use upon aprons of all descriptions, it is also applicable to various other types of shoulderless garments, such as dresses, frocks or gowns, bathing suits, and the like.

The invention has as an object the provision of a specially constructed shoulderless garment with a prehensile spring supporter detachably connected to the interior of the garment and adapted to resiliently engage the waist and chest of the wearer, to hold the garment in proper position upon the body of the wearer, without the aid of sleeves, shoulder straps or other means for supporting the bib, or upper portion of the garment over the bosom of the wearer, without danger of injury to the wearer or the garment.

Another object is to provide such a garment and spring supporter which may be quickly and easily put on or removed, so that in the event of an apron or the like, made in accordance with the invention, catching fire or becoming caught in moving machinery, it may be removed in a fraction of a second, since there are no strings to untie, or buttons or other fastening devices to unfasten.

A further object of the invention is to provide a garment of the character referred to, having an open-ended casing or tubular pocket at its upper edge, to receive a portion of the spring supporter, and having a similar casing at the front of the waist portion and pockets at the back of the waist portion for receiving other portions of the spring supporter, whereby the spring supporter may be detachably assembled within the garment for use, and may be removed therefrom to permit washing or cleaning of the garment.

A still further object is to provide a spring supporter formed of a single spring wire, the central portion of which is formed into substantially an inverted U-shape, for connection to the bib, or upper front portion of the garment, opposite ends of the spring wire being curved rearwardly to be received in the pockets at the rear of the garment, and then curved forwardly, terminating at points slightly spaced from each other and adapted to be received within the open-ended casing, or tubular pocket, within the waist portion of the garment.

2

The above objects together with others which will be apparent from the drawings and following description, or which may be later referred to, may be attained by constructing the improved shoulderless garment and supporter in the manner hereinafter described in detail and illustrated in the accompanying drawings, in which:

Fig. 1 is a perspective view of the prehensile spring supporter forming a part of the invention;

Fig. 2 a side elevation of the spring supporter;
Fig. 3 an inside plan view of a workman's apron constructed in accordance with the invention, with the spring supporter removed therefrom;

15 Fig. 4 a front perspective view of a workman's apron and spring supporter embodying the invention, showing the garment as it appears upon the wearer;

Fig. 5 a rear perspective view of the garment shown in Fig. 4;

Fig. 6 a front perspective view, similar to Fig. 4, showing an apron of the type worn by housewives with the spring supporter associated therewith;

20 Fig. 7 a rear perspective view of the apron and supporter shown in Fig. 6;

Fig. 8 a front perspective view of a sunback dress or the like embodying the invention;

Fig. 9 a rear perspective view of the dress shown in Fig. 8; and

Fig. 10 a front perspective view of a bathing suit embodying the invention.

Referring first to the embodiment of the invention shown in Figs. 1 to 5, the invention is 35 illustrated as applied to a workman's apron 15 having the bib portion 16, at the upper end of which is provided the open-ended casing or tubular pocket 17.

A similar open-ended casing or tubular pocket 40 18, preferably of greater length than the casing 17, is located within the front portion of the apron at the waist line, and at each side edge of the apron, substantially in line with the casing 18, a relatively small pocket 19 is provided, 45 closed at its outer end and preferably adapted to be adjusted as to length by means of the snap fastener 20 adapted for engagement with any one of the plurality of snap fasteners 21, for different waist sizes.

50 From an inspection of Fig. 3, it will be obvious that with the pockets 19 in normal position, as shown at the left side of said figure, the pockets 19, as well as the waist line of the garment, are of greatest length. By folding the outer end 55 of each pocket 19 upon itself so as to connect

the snap fastener 20 with the outermost snap fastener 21, as indicated at the right side of Fig. 3, the pockets 19 and waist line of the garment will both be somewhat shortened.

In like manner, both the pockets 19 and waist line may be further shortened by connecting the snap fasteners 20 with the intermediate snap fasteners 21, and the minimum length of pockets and waist line may be obtained by connecting the snap fasteners 20 with the innermost snap fasteners 21.

It will be evident that as the waist line of the garment is thus reduced or increased, to accommodate the wearer, the terminal ends 27 of the spring wire supporter are free to move toward or from each other in the open-ended casing 18 at the front of the garment.

The supporter, best shown in Figs. 1 and 2, is in the form of a prehensile spring member made of a single length of spring wire, including the intermediate, inverted, U-shaped portion 22 with forwardly disposed, substantially horizontal intermediate upper portion 23, adapted to be received within the casing or tubular pocket 17 at the upper edge of the bib portion 16 of the apron.

On each side of this inverted U-shaped portion, the wire is curved downward and rearward, as at 24, and thence in the opposite direction, as at 25, forming reversely bent rounded terminal ends to be received in the pockets 19 of the apron, and then curved forwardly, in a substantially horizontal plane, as at 26, terminating in the spaced apart terminal eyes or loops 27, for reception through opposite open ends of the casing or tubular pocket 18 at the front of the waist portion of the apron.

When the spring supporter is thus detachably connected to the apron 15, and the apron is positioned upon the body of a wearer, as shown in Figs. 4 and 5, it will be seen that the intermediate horizontal portion 23 of the spring supporter will fit across the chest of the wearer; the downwardly and rearwardly curved portions 24 of the spring supporter extend along the sides of the bib portion 16 of the apron and grasp the sides of the wearer's body, the reversely curved terminal portions 25 thereof fitting around the back of the wearer near the waist line, holding the bib portion of the apron in place against the front of the wearer's body and holding opposite side portions of the apron together at the back of the wearer's body, while the forwardly curved terminal portions 26 of the spring supporter, located within the casing 18 of the apron, hold the front portion of the apron around the wearer's waist.

With an apron and supporter of this type, it will be seen that it is only necessary to flex the curved portion 24 of the supporter apart in order that the spring member is properly positioned upon the body of the wearer, and that in the case of an emergency, such as the apron catching fire or being caught in a piece of moving machinery, it may be instantly removed from the body of the wearer in a single movement, since there are no strings to untie, or buttons or other fastening devices to unfasten. This is a highly important safety factor of the garment and supporter embodying the invention.

When the apron provided with this spring supporter is worn it will remain in proper position upon the wearer's body permitting freedom of movement in any direction without dislodging the apron.

In Figs. 6 and 7 is shown the application of

the invention to a woman's apron, such as may be worn as a housewife. The apron, indicated generally at 15a, may be of any conventional type provided with a bib or upper portion 16a, having an open-ended casing or tubular pocket 17a at its upper edge, an open-ended casing or tubular pocket 18a on its inner side around the waist line, and the relatively short pockets 19a at each side edge, substantially in line with the casing 18a and adapted to be located slightly spaced apart at the back, as shown in Fig. 7.

The spring supporter may be the same as shown in Fig. 1, and is adapted to be detachably connected to the inner side of the apron in the manner illustrated and described with reference to Figs. 4 and 5; the horizontal, intermediate portion 23 thereof being received within the upper open-ended casing 17a, the return bent terminals 25 being received in the pockets 19a at the back of the apron, and the terminal ends 27 being received in the open-ended casing 18a in the front of the apron.

Thus the apron is detachably supported upon the body of the wearer and flexibly or resiliently held in place over the bosom and around the waist, permitting free movement of the body without accidentally displacing the apron, and at the same time permitting the apron to be instantly removed in case of an emergency.

In Figs. 8 and 9 the invention is shown as applied to the dress or frock, such as a sunback dress indicated generally at 15b, having the upper front portion 16b provided with the open-ended casing or tubular pocket 17b at its upper edge, to receive the horizontal, intermediate portion 23 of the wire supporter, the relatively small pockets 19b at the back, to receive the return bent terminals 25 of the wire supporter, and the open-ended casing or tubular pocket 18b within the front of the garment at the waist line, to receive the terminal ends 27 of the supporter.

The garment is thus resiliently held snugly in position upon the body of the wearer, the upper portion 16b thereof being held over the bosom of the wearer without the use of shoulder straps, sleeves or the like.

In Fig. 10 is shown the application of the invention to a bathing suit indicated generally at 15c, the upper front portion 16c thereof being strapless and having the reversely curved upper edge 16', around which is located the similarly shaped open-ended casing or tubular pocket 17c.

The wire supporter used for this bathing suit may be the same as shown in Fig. 1, with the exception that the intermediate portion 23c is reversely curved so as to be received within the casing 17c.

The return bent terminals 27 of the supporter are received within pockets (not shown) located in the back of the garment and similar to the pockets 19, 19a and 19b in Figs. 5, 7 and 9 respectively.

An open-ended casing or tubular pocket 18c is formed within the front portion of the bathing suit, at the waist line, to receive the terminals 25 of the supporter. The bathing suit is thus held snugly upon the body of the wearer, the upper portion 16c thereof being held in position without the use of shoulder straps or the like.

It will thus be evident that the combination shoulderless garment and supporter are adapted to carry out the objects of the invention, the supporter effectively holding the garment in proper position upon the body of the wearer and

permitting free movement of the body when being worn, the construction of both the garment and supporter being very simple and the supporter being adapted to be readily assembled to or removed from the garment, and in the case of an apron, the supporter permitting instant removal of the apron in the event of an emergency.

In the foregoing description, certain terms have been used for brevity, clearness, and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. In combination with a shoulderless garment comprising a nether portion having a pair of adjacent inside pockets at the back and near the waist line which are open at their inner ends only, and an upper front portion having a casing along its upper edge which is open at its ends, and an inside casing at the front of the garment near the waist line which is open at its ends, a supporter for the garment comprising a prehensile spring member made of a single spring wire including an intermediate inverted U-shaped portion having a forwardly curved intermediate portion removably seated in said first named casing and adapted to fit across the chest of the wearer, downwardly and rearwardly curved side portions constituting continuations of opposite ends of said inverted U-shaped portions and adapted to grip the sides of the wearer's body, lateral rearwardly curved portions constituting continuations of said side portions and which extend toward each other to fit around the back of the wearer near the waist line, reversely bent terminal portions constituting continuations of said rearwardly curved portions and which are seated in the pockets of the nether portion and lateral forwardly curved terminal end portions constituting continuations of said reversely bent terminal portions and which extend toward each other to fit around the waist line of the wearer and are removably seated in said second named casing.

2. In combination with a shoulderless garment comprising a nether portion having a pair of adjacent inside pockets at the back and near the waist line which are open at their inner

ends only, means for adjusting the length of said pockets to adjust the length of the waist line of the garment, and an upper front portion having a casing along its upper edge which is open at its ends, and an inside casing at the front of the garment near the waist line which is open at its ends, a supporter for the garment comprising a prehensile spring member made of a single spring wire including an intermediate inverted U-shaped portion having a forwardly curved intermediate portion removably seated in said first named casing, and adapted to fit across the chest of the wearer, downwardly and rearwardly curved side portions constituting continuations of opposite ends of said inverted U-shaped portion and adapted to grip the sides of the wearer's body, lateral rearwardly curved portions constituting continuations of said side portions and which extend toward each other to fit around the back of the wearer near the waist line, reversely bent terminal portions constituting continuations of said rearwardly curved portions and which are seated in the pockets of the nether portion and lateral forwardly curved terminal end portions constituting continuations of said reversely bent terminal portions and which extend toward each other to fit around the waist line of the wearer and are removably seated in said second named casing.

3. A supporter for shoulderless garments, said supporter comprising a single spring wire including an intermediate inverted U-shaped portion having a forwardly curved intermediate portion adapted to be seated in a horizontally elongated open-ended casing at the top of the front portion of a garment, downwardly and rearwardly curved side portions constituting continuations of opposite ends of said inverted U-shaped portion, lateral rearwardly curved portions constituting continuations of said side portions and which extend toward each other, reversely bent terminal portions constituting continuations of said rearwardly curved portions and which are adapted to be seated in pockets at the back of a garment near the waist line thereof, and lateral forwardly curved terminal end portions constituting continuations of said reversely bent terminal portions and which extend toward each other and are adapted to be seated in an open-ended casing in the front of a garment near the waist line thereof.

PAUL R. SWEARINGEN.
